UNITED STATES PATENT OFFICE.

HARRY McTAVISH, OF ELDON, PRINCE EDWARD ISLAND, CANADA.

FOLDING BOX OR CRATE.

1,105,285.

Specification of Letters Patent. Patented July 28, 1914.

Application filed May 23, 1913. Serial No. 769,439.

To all whom it may concern:

Be it known that I, HARRY McTAVISH, a subject of the King of Great Britain, residing at Eldon, in the Province of Prince Edward Island, Canada, have invented a new and useful Folding Box or Crate, of which the following is a specification.

My invention relates to folding boxes and crates, and the object is to provide a cheap, simple but strong and durable shipping box or crate, which when empty may be folded so as to occupy but little space during its return to the shipping point, where it may be filled and shipped again.

15 In the accompanying drawing,—Figure 1 is a top view of a shipping box set up and closed and embodying my improvements. Fig. 2 is a side elevation of the box shown in Fig. 1. Fig. 3 is a longitudinal vertical section on the line *a—a* Fig. 1. Fig. 4 is an enlarged end elevation of the box shown in Fig. 1. Fig. 5 is a top view of the box folded. Fig. 6 is the same as Fig. 5 with the side sections 7 of the box unhinged and removed. Fig. 7 is an enlarged end view of the folded box shown in Fig. 5. Fig. 8 is a horizontal sectional view of one end of the box, as on the line *b—b* Fig. 4.

Referring to the drawing by reference numerals. 1 designates the bottom of the box. Upon each end of the bottom is secured a transverse cleat 2, and at the inner edge thereof is fastened by hinges 3 one of the inwardly foldable end sections 4 of the box. 35 Said end sections are at each end provided with a cleat 5, which is preferably of angular or L-shaped cross section, as shown.

The sides of the box are each composed of a lower and an upper section; the lower section 6 is rigidly fixed to the bottom and the upper and larger section 7 is hinged at 8 to the upper edge of the fixed section, to fold inward and substantially reach the opposite section, as shown at A in Fig. 5. At 45 the ends of each section 7 are fixed L-shaped cleats 9 which together with the section form grooves into which the cleats 5 of the end sections pass when the box is set up. In

such vertical position the side sections 7 are held by the top piece or cover 10, which is 50 inserted between them and rests upon the top edges of the end sections 4, and the latter sections are prevented from folding inward by cleats 11 fixed at the under side of each end of the cover.

55 The cover is held down in place by the projecting ends 11^a of the cleats 11, engaging under a longitudinal rim 12 of one of the sections 7, and a latch 13 pivoted at 14 upon the cover and by a spring 15 held engaged under a plate 16 secured upon the other rim 12.

60 To fold the box, as in Figs. 6 and 7, the end sections 4 are folded inward flat upon the bottom, the cover 10 is placed upon the end sections between the cleats 5, preferably with the cleats upward so that their projecting ends 11^a will pass into the angular grooves of the cleats 5, as shown to the left in Fig. 7. The side sections 7 are then 65 folded inward upon the cover and secured in folded position by a springy hook 17, which is pivoted at 18 to one section and tightly engaged with a headed stud 19 on the other section. When said hook is idle it is tightly 70 engaged a stud 20, as shown in Fig. 2, so as not to swing about and get bent or broken.

75 Although I have shown only a box embodying my invention, it is obvious that it is just as applicable to shipping crates of 80 almost every description.

What I claim is:

In a folding box, the combination with a bottom, of sections hinged thereto to fold inward upon the bottom and having cleats 85 upon the outer sides of its vertical edges, side sections composed each of a rigid portion secured to the bottom and an upper portion hinged thereto and provided at its ends with grooved cleats in which to receive the 90 cleats of the end sections when the box is set up, a cover adapted to rest upon the ends of the end sections and having cross cleats by which to engage the end sections and prevent their folding, and means for holding 95 said cover in place when the box is set

up; the width of said cover being such as to make it fit between the cleats of the end sections when the latter are folded inward and the cover is placed upon them, and the hinged side sections being so held by the rigid side sections as to fold in level position upon the cover and reach substantially together upon the same, and means for hold-

ing the hinged side sections in said folded position.

In testimony whereof I affix my signature, in presence of two witnesses.

HARRY McTAVISH.

Witnesses:

K. J. MARTIN,
MYRTLE CAMERON.
